(57) CLAIM

We claim the ornamental design for a basketball basket container, as shown herein.

DESCRIPTION

FIG. 1 is a perspective view of a basketball basket container showing our new design;

FIG. 2 is a front view thereof;

FIG. 3 is a side view thereof;

FIG. 4 is a back view thereof;

FIG. 5 is a top view thereof; and,

FIG. 6 is a bottom view thereof.

The broken line showing in FIGS. 1, 2 and 5 is for illustrative purposes only and forms no part of the claimed design.
